MANUALLY OPERATED PRESS

Patrick J. Kearney, Toronto, Ontario, Canada

Application November 21, 1932
Serial No. 643,712

9 Claims. (Cl. 153—48)

My invention relates to improvements in manually operated presses and the object of the invention is to devise a hand operated press particularly suitable for use in machine shops, garages and the like for straightening axles, shafting, removing couplings from shafting, pressing in bushings and work of similar nature.

A further object is to devise a press which will be capable of taking care of work whether the latter is in the horizontal or vertical position, and a still further object is to devise a press which can be readily and easily operated by hand through the employment of a non-elastic fluid to exert very high pressure on the work.

My invention consists in its preferred embodiment of a press constructed and arranged all as hereinafter more particularly described and illustrated in the accompanying drawings in which,

Fig. 1 represents a front elevation thereof.

Fig. 2 is a side elevation, the dotted lines indicating an alternative horizontal position assumed by the press frame when it is desired to press couplings off long shafts.

Fig. 3 is an enlarged plan view.

Fig. 4 is a further enlarged vertical section through the cylinder and pump used in connection with my device showing the means for admitting the non-elastic fluid to the cylinder 30 and returning it to the tank or reservoir.

Fig. 5 is a further enlarged plan view of the means for admitting the non-elastic fluid to the pump and returning it to the reservoir.

Fig. 6 is a vertical section through the line 35 6—6, Fig. 5, and,

Fig. 7 is a vertical section through the line 7—7, Fig. 5.

Like characters of reference indicate corresponding parts in the different views.

My press has a base plate 1 of its frame connected to a base 2 so that the frame may be swung to assume either a vertical or a horizontal position, depending upon whether the work is located in a horizontal or a vertical position. A transverse member 3 extends between the vertical stanchions 4 of the frame and is adapted to support the cylinder 5 as well as the upper transverse member 6 through the medium of interposed I-beams 7. The upper transverse member 6 has the reduced ends of the stanchions

extending therethrough and nuts 8 are threaded on the upper ends of such reduced ends.

A table for the work may well comprise the two spaced apart I-beams 9 which are secured to the base plate 1 of the frame, which base plate 55 is adapted to rest upon the base 2 when the frame is in the vertical position and be secured thereto by means of the bolts 10.

Main stanchions 11 positioned between the stanchions 4 extend up from the base plate 1 of the frame and their reduced upper ends extend through the transverse members 3 and 6, being provided with nuts 12 threaded on to the upper ends adapted to be screwed down upon the upper transverse member 6.

The cylinder 5 is open at its lower end and receives the plunger 13, the lower end of said plunger protruding from the cylinder and being adapted to engage the work to be acted upon. The upper end of the plunger 13 is provided with 70 a leather or other suitable disc 14 to act as an obturating medium between the cylinder wall and the plunger.

A tubular member 15 extends upwardly from the cylinder 5 to a member 16 which carries a 75 relief valve 17, the member 16 having a vertical orifice 18 with which the tubular member 15 communicates and the upper end of the vertical passageway 18 also communicates with a pump cylinder 19 provided with a reciprocable plunger 22. 80 A packing 21 is positioned in an enlarged upper portion 20 of the pump cylinder 19 and surrounds the plunger 22. A stuffing box 23 is threaded on to the upper end of such pump cylinder 19, the upper end of the plunger 22 protruding through 85 the stuffing box and carrying a fork 24 which is pivotally connected to the handle 25 fulcrumed on the bracket 26. The bracket 26 is secured upon one of the I-beams 7. The free end of the pump handle lever 25 is provided with a counterweight 27, and hinge links 28 mounted on the same I-beams 7 are provided with longitudinal slots 29 into which laterally extending pins 30 on the handle 25 extend, such links acting as means for limiting the upward and downward 90 movement of the operating handle of the pump.

Laterally extending hook members 31 extend outwardly from the plunger 13, over which are hooked the lower ends of the upwardly extending rods 32 which have enlarged upper portions 100

33 connected together by the yoke 34, such rods 32 extending freely through the upper flange 35 of the cylinder 5, and compression springs 36 are provided on such rods between the upper face of 5 the flange 35 and the lower ends of the enlarged portions 33.

A reservoir or tank 37 for the reception of the non-elastic fluid such as oil is provided, preferably on one of the I-beams 7, and an oil supply 10 pipe 38 extends from such tank to a passageway 39 which extends upwardly through the member 16 being provided with a check valve 40 which is preferably spring-held on its seat 41 by means of the spring 42. The upper end of the passageway 39 is provided with a closure or plug 43 and such passageway 39 communicates with a transverse passageway 44 which in turn communicates with the above referred to passageway 18 which is in turn provided with a check valve 45 adapted 20 to rest on the seat 46 and spring-held thereon by means of the spring 47, such check valve adapted to open in the opposite direction to the check valve 40.

Disposed below the valve seat 46 is a diagonal passageway 48 extending from the passageway 18 and adapted to communicate with the passageway 49 which is connected at its outlet end by a pipe 50 with the reservoir or tank 37. When the relief valve 17, which is positioned to close the 25 passageway 48, is screwed down, such valve prevents the return of oil or other non-elastic fluid from the passageway 48 to the passageway 49, such relief valve being preferably provided with a lever handle 51.

30 A pipe 52 leading from the cylinder 5 to a pressure gauge 53 is provided to indicate the pressure in the cylinder 5.

The device operates as follows:—

The work is placed on the table constituted 40 by the I-beams 7 and non-elastic fluid is admitted into the passageway 18 of the member 16 from the tank 37 through the pipe 38 and passageways 39 and by pulling up the pump handle 25, thus causing the pump plunger 22 45 to move upwardly in the pump cylinder 19 creating a suction in the passageway 18 which draws the non-elastic fluid from the tank therewith.

Upon the pump handle 25 being then moved 50 downwardly the liquid in the passageway 18 is forced through the check valve 45 into the tube 15 and from thence into the cylinder 5. Further reciprocation of the pump plunger will cause the pressure in the cylinder 5 to be built 55 up to the required extent, forcing down the plunger 13 into engagement with the work and causing such plunger to exert pressure upon such work.

The check valve 45 prevents the fluid backing up in the passageway 18 on the suction stroke 60 of the pump, it being assumed of course that in introducing fluid to the cylinder 5 the relief valve 17 is closed.

Upon releasing the fluid pressure in the cylinder 5 by opening the relief valve 17, the springs 65 36 will return the plunger 13 to its initial position illustrated in Fig. 4 and force the fluid in the cylinder 5 back into the tank 37, said fluid flowing back through the tubular member 15, into the passageways 48 and 49 into the return pipe 50 and thence to the tank 37.

70 It is found that by the use of the hand pump above described, depending of course upon the size of the cylinder 5, a pressure of as much as fifty tons can be exerted on the work, such as an axle or shaft to be straightened, without

undue effort on the part of the operator. Consequently a device of the above type, free from the necessity and complications of being power driven, will be of considerable use in small shops and garages and especially in places unprovided with a source of power supply. 80

What I claim as my invention is:

1. In a press, a base portion having an abutment at its top, a pressure exerting element supporting frame having an abutment at its bottom, and a hinged connection between the frame and the base portion for enabling the frame to be swung to a horizontal position clear of the base portion, the frame abutment resting on the base abutment when the frame is in the vertical position and supporting such frame on its base portion. 85

10 2. In a press, a base portion comprising leg brackets each with a flat substantially horizontal top, a pressure exerting element supporting frame including a flat plate at its lower end, and hinges at an edge of the plate connecting the same with the flat portions of the leg brackets for enabling the frame to be swung to a horizontal position clear of the base portion, 90 the plate of said frame resting on the flat portions of the leg brackets when the frame is in an upright position.

15 3. In a press, the combination with a cylinder adapted to receive non-elastic fluid pressure, a plunger reciprocable therein having a work engaging portion protruding from the cylinder, a source of non-elastic fluid supply, a pressure pump, an integrally formed member between the pressure pump and the cylinder upon which the 105 pump is directly mounted including a passageway formed therein and communicating with the pressure pump and cylinder, a check valve in the passageway permitting the admission of fluid pressure into the cylinder, a second passageway 110 formed in the member communicating with the first passageway above the check valve, the second passage connected to the source of fluid supply, and a check valve in the second passageway for preventing retrograde movement of the fluid 115 therethrough.

4. In a press, the combination with a cylinder

120 adapted to receive non-elastic fluid pressure, a plunger reciprocable therein having a work engaging portion protruding from the cylinder, a 125 source of non-elastic fluid supply, a pressure pump, an integrally formed member between the pressure pump and the cylinder upon which the pump is directly mounted including a passageway 130 formed therein and communicating with the pressure pump and cylinder, a check valve in the passageway permitting the admission of fluid pressure into the cylinder, a second passageway formed in the member communicating with the first passageway above the check valve, the second 135 passage connected to the source of fluid supply, a check valve in the second passageway for preventing retrograde movement of the fluid therethrough, a return fluid passageway formed in the member and extending from below the 140 check valve in the first passageway and connected with the source of fluid supply, and relief valve for normally closing said return fluid passageway.

145 5. In a press, the combination with a pressure cylinder open at its lower end and a plunger reciprocable therein having a work engaging portion protruding from the cylinder, said plunger being withdrawable through the open end of the cylinder, of a flange on the cylinder, rods extend- 150

ing freely through the flange and connected at their lower ends to the protruding work engaging portion of the plunger, a yoke connecting the upper ends of the rods, and compression springs on said rods disposed between the cylinder flange and the yoke.

6. In a non-elastic fluid cylinder press of the pressure pump actuated type, a non-elastic fluid controlling device comprising an integrally formed member mounted on the head of the working cylinder and having a fluid passageway extending therethrough and communicating at one end with the cylinder, the other end of the passageway communicating directly with the pressure pump, a check valve in the passageway adapted to open in the direction of the working cylinder, a fluid inlet passageway formed in the member extending from the exterior thereof in communication with the first passageway between the check valve therein and its pump connected end, a check valve in the fluid inlet passageway for preventing retrograde movement of the fluid therethrough, a return fluid passageway formed in the member and communicating with the first passageway between the check valve and its cylinder connected end, the other end of the return fluid passageway extending to the exterior of the member, and a relief valve in said return fluid passageway.

30 7. In a controlling device as claimed in claim 6, wherein said return passageway extends diagonally through the member to an upper corner thereof, and a subsidiary branch extends from the

upper end of the return passageway to the exterior of the member, the relief valve being located at the junction of the return passageway and its subsidiary branch.

8. In a non-elastic fluid operated press, the combination with the working cylinder having an open lower end, a plunger inserted into said cylinder and having a lower work engaging end protruding therefrom, a fluid pressure pump mounted above the cylinder head and including a vertically swingable actuating lever and resilient means for restoring the plunger to its uppermost position in the cylinder, said means limiting the stroke of the actuating lever as fluid pressure is built up by the pump in the working cylinder thereby preventing the ejection of the plunger from the cylinder.

9. In a non-elastic fluid operated press, the combination with the working cylinder having an open lower end, a plunger inserted into said cylinder and having a lower work engaging end protruding therefrom, a fluid pressure pump mounted above the cylinder head and including a vertically swingable actuating lever, an external flange on the cylinder, vertical rods extending therethrough and connected at their lower ends to the protruding work engaging end of the plunger, a yoke connecting the upper ends of the rods and straddling the pump actuating lever, and springs on the rods interposed between the yoke and the cylinder flange.
